US00D806727S

(12) **United States Design Patent** (10) Patent No.: **US D806,727 S**
Park et al. (45) Date of Patent: ** **Jan. 2, 2018**

(54) **DISPLAY SCREEN WITH GRAPHICAL USER INTERFACE**

CPC G06F 3/048; G06F 3/0481; G06F 3/0482;
G06F 3/04817; G06F 3/04812

(71) Applicant: **LG ELECTRONICS INC.**, Seoul
(KR)

(56) **References Cited**

U.S. PATENT DOCUMENTS

(72) Inventors: **Junsic Park**, Seoul (KR); **Uniyoung Kim**, Seoul (KR); **Gangseub Lee**, Seoul (KR); **Seungwon Ryu**, Seoul (KR); **Yoonna Soh**, Seoul (KR); **Sowoon Yoon**, Seoul (KR); **Sunghwa Jang**, Seoul (KR)

(73) Assignee: **LG ELECTRONICS INC.**, Seoul
(KR)

(**) Term: **15 Years**

(21) Appl. No.: 35/501,637

(22) Filed: Mar. 30, 201

(80) **Hague Agreement Data**

Int. Filing Date: Mar 30, 2016

Int. Reg. No.: **DM/091861**

Int. Reg. Date: **Mar. 30, 2016**

Int. Reg. Pub. Date: Sep. 30, 2016

(30) Foreign Application Priority Data

Sep. 30, 2015 (KR) 30-2015-0049491

(51) LOC (11) Cl. 14-94

(52) U.S. Cl.

USPC D14/485

(58) Field of Classification Search

USPC D14/485-495; D20/12; 709/225;
715/746, 771, 739

are for the purpose of illustrating portions of the graphical user interface and forms no part of the claimed design.
